UNITED STATES PATENT OFFICE.

FRANZ A. FULLER, OF NEWARK, NEW JERSEY, ASSIGNOR TO J. E. MERGOTT COMPANY,
OF NEWARK, NEW JERSEY, A CORPORATION OF NEW JERSEY.

LIP-STICK HOLDER.

1,290,164.

Specification of Letters Patent.

Patented Jan. 7, 1919.

Application filed May 28, 1918. Serial No. 237,007.

To all whom it may concern:

Be it known that I, FRANZ A. FULLER, a citizen of the United States, residing in the city of Newark, county of Essex, and State of New Jersey, have invented certain new and useful Improvements in Lip-Stick Holders, of which the following is a full, clear, and exact description, such as will enable others skilled in the art to which it pertains to make and use the same, reference being had to the accompanying drawings, and to the figures of reference marked thereon, forming a part of this specification.

This invention has reference to improvements in holders for lip-sticks of rouge, the primary object of my invention being to simplify the structure so as to render the same positive yet effective in operation, simple and inexpensive in construction, and durable in use.

A further object of my invention is to produce the various parts comprising the device, from ordinary sheet metal by the use of suitable punches and dies, thereby reducing the cost of manufacture to a minimum.

With these ends in view, my invention consists of certain novelties of construction and arrangement of parts, as hereinafter set forth and pointed out in the claims. While the preferred form of my invention is illustrated in the accompanying drawings, yet it is to be understood that minor changes may be made without departing from the scope thereof.

In the drawings,

Figure 1 represents a side elevation of the lip-stick holder with the cap applied.

Fig. 2 represents a similar view illustrating the holder with the cap removed.

Fig. 3 represents a side elevation of the holder with the follower and rouge stick secured therein.

Fig. 4 represents an end view of the same.

Fig. 5 represents a transverse section taken on lines $w-w$ of Fig. 2, and

Figs. 6, 7, and 8 represent, respectively front, rear and end elevations of the follower.

Similar numerals of reference refer to like parts throughout the specification and drawings.

In the drawings, 1 represents the holder proper, 2 the follower, and 3 the cap. All these parts are preferably elliptical in cross-

section, closed at one end and open at the other. The parts are of such shape as to lend themselves readily to manufacture by the use of suitable punches and dies, from ordinary sheet metal, and which parts are reduced to the simplest operative efficiency. The holder is so constructed from a single piece of flat metal, as to provide a longitudinal slot 5 extending throughout the greater portion of its length, and along one side, terminating at its ends short of the ends of the holder. In close proximity to the open end of the holder 1, are formed in any desired or convenient manner, preferably by being struck out from the metal of said holder, a plurality of inwardly extending prongs or lugs 9 designed to be engaged by the follower 2, after said follower has been slidably arranged within the holder 1. The object being to limit the outward movement of the follower 2 in the holder 1.

The holder being formed from a single piece of suitable material adjacent to its open end thereof, where the edges of the material come together or abut is slightly cut away to provide, preferably a V-shaped notch 4 for the reception of the tongue formed on the follower 2, to be presently described. The cap 3 is also made from a suitable piece of sheet metal, and proportioned to fit snugly over the holder 1, and in its preferred form is provided, adjacent to either end, with outset annular beads for the sake of ornamentation. Its open end is also provided with diametrically oppositely arranged notches 14, adapted to align with the slot 5 of the holder. The follower 2 is also made from a single piece of suitable material, so formed as to provide adjacent to the open end thereof, a tongue 6. The tongue is formed in the follower in such a manner, that when the follower is located within the holder, the tongue will be projected through the slot. This follower is proportioned to fit snugly within the holder and to slide therein, and the rouge stick is proportioned so that one end will seat in the follower, being held thereto by one or more prongs 7, struck from the follower, so that the stick as a whole may be in the holder proper, or projected beyond the open end of the holder, as desired, throughout the movement of the follower. This tongue 6 forms an integral part of the flat blank, from which the follower 2 is made, and is of a sufficient length

to be folded upon itself to form a convenient finger piece 8 by means of which the follower with its attached rouge stick can be manipulated.

5. In assembling the device the follower is slipped into the open end of the holder, with its closed end innermost, and with its tongue in alinement with the V-shaped notch 4 in the end of the holder, so that when pressure is exerted the tongue will enter the notch, thereby causing the meeting edges of the holder, located between the bottom of the notch and the bottom of the slot, to spread sufficiently to permit the tongue to snap into, 10 and have sliding engagement with the slot in the holder. The object of providing the open end of the cap with the two alined notches 14 is to provide means whereby the tongue 6 of the follower will always engage 15 with one of said notches, irrespective of the manner in which the holder is inserted in the cap.

Experience has demonstrated that the organization above described is a highly efficient one, and while I have shown the preferred embodiment of my present invention, I do not wish to be limited to the exact details of construction shown and described, as obvious modifications thereof, not involving 25 the exercise of invention, may be made by any skilled mechanic, and such departures from what is herein set forth, I consider within the scope and terms of my claims.

I claim:—

35. 1. A lip stick holder comprising a tubular holder, closed at one end, said holder being formed from a flat piece of material with a longitudinal slot terminating short of its ends and provided with a notch adjacent its open end, a follower formed from a flat piece of material slidably arranged within the holder, to receive a stick of rouge, a tongue formed on the follower and project-

ing through the slot of the holder, the tongue being bent to provide a finger piece projecting beyond the holder and by means of which the stick may be reciprocated within the holder, and a cap having sliding engagement with the holder formed from a flat piece of material with one end open to receive the holder, and the other end closed, said open end being provided with alined notches for the reception of the tongue of the follower.

2. A lip stick holder comprising a tubular 55 holder formed from a flat piece of material having a longitudinal slot formed by the edges of said material, terminating short of its ends, and further provided with a notch adjacent its open end, integral stops projecting inwardly and located adjacent said open end, a follower formed from a flat piece of material slidably arranged within said holder adapted to receive a stick of rouge, the movement in one direction of said follower being limited by the said integral stops, said follower being provided with instruck integral rouge holding means, a tongue formed on the follower and projecting through the slot of the holder, the 70 tongue being bent to provide a finger piece projecting beyond the holder and by means of which the stick may be reciprocated within the holder, and a cap having sliding engagement with the holder formed from a 75 flat piece of material with one end open to receive the holder, and the other end closed, said open end being provided with alined notches for the reception of the tongue of the follower.

This specification signed and witnessed this 22nd day of May, 1918.

FRANZ A. FULLER.
